UNITED STATES PATENT OFFICE.

WILLIAM S. WILLS AND ROBERT A. ROGERS, OF OKLAHOMA, OKLAHOMA.

BURGLAR-ALARM FOR AUTOMOBILES.

1,366,855.

Specification of Letters Patent. Patented Jan. 25, 1921.

Application filed May 7, 1920. Serial No. 379,664.

To all whom it may concern:

Be it known that we, WILLIAM S. WILLS and ROBERT A. ROGERS, citizens of the United States, and residents of Oklahoma city, in 5 the county of Oklahoma and State of Oklahoma, have invented certain Improvements in Burglar-Alarms for Automobiles, of which the following is a specification, reference being had to the accompanying 10 drawings.

The object of the invention is to provide means for giving an alarm when an unauthorized person attempts to start an automobile.

15 Figure 1 of the drawings is a plan view showing one of the practical forms in which the invention may be embodied.

Fig. 2 is a sectional view taken on the line 2—2 of Fig. 1, but showing nothing but 20 an inclosing casing and the contained parts of a combination lock mechanism.

Fig. 3 is a plan view of the bottom of the inclosing casing.

Fig. 4 is an inverted plan view of the 25 upper or cover portion of the casing and the parts contained therein.

Fig. 5 is a fragmental reproduction of Fig. 4, but shows a different position of certain parts.

30 Fig. 6 is a similar view, but shows still another position of said parts.

Fig. 7 is a sectional view taken on the line 7—7 of Fig. 6.

Like characters of reference designate 35 like parts in all the figures.

For convenience of this description, certain electric switches and an electric bell are represented by the usual electric symbols and shown mounted on bases of material 40 which properly insulate them from other parts.

Batteries and other sources of current which do not require specific description are omitted from the drawings.

45 In carrying out the object stated, there is provided a casing 10 strong enough to protect locking mechanism and electric switches, and this casing is adapted to be attached to some suitable part of the automobile in such 50 manner that it cannot be readily removed.

The casing 10 includes a bottom 11 and top 12, the latter having integral side walls 13 and end walls 14 and 15 which fit the rabbeted edges 16 of the bottom.

55 The bottom 11 and top 12 are secured to-

gether by screws 17, and any suitable means may be provided for rendering the heads 18 of these screws inaccessible to unauthorized persons.

At one corner of the interior of the casing 10 the tumbler mechanism of a combination lock is arranged.

In arranging this tumbler mechanism, a depending annular seat 19 is cast integrally with the cover 12, and a supporting base 20 65 is secured to the lower face of said seat by screws 21.

This base 20 is provided centrally with the usual pivotal stud 22, on which disks or tumblers 23 are mounted to revolve, each 70 tumbler being provided at its edge with the usual notch 24.

A knob 25 is mounted on the outer surface of the top 12 with its spindle 26 journaled through said top and concentric with the 75 stud 22, the inner end of the knob spindle 26 being provided with a disk 27 which is itself provided with an edge notch 24 and serves as a tumbler.

The disk 27 and the tumblers 23 are provided with the usual face studs 28, so that by 80 revolving the knob 25 the notches 24 of the tumblers may be alined.

In further arrangement, a switch-operating bar 29 is mounted slidably in the casing 85 10 on a line preferably intersecting the pivotal axis of the tumblers 23, the end of this bar adjacent said tumblers being guided by a bearing 30 on the cover 12 and the outer end being guided by passing through the 90 wall 15.

With the bottom 11 and top 12 of the casing 10 assembled, a stud 31 on the bottom forms a separable portion of the bearing 30 in guiding the bar 29; and in order to allow 95 the end of the bar to enter the notches 24 of the tumblers 23 and disk 27 an opening 32 is provided in the seat 19.

The electric switch 33 of the ignition circuit, or one or more of the other switches 100 used, may be contained in the casing 10 and secured to a block 34 mounted on the cover 12, this switch being operated by the bar 29 through a suitable connecting-rod 35.

The wiring 36 from this switch 33 may 105 lead out of the casing 10 through a suitable protecting conduit 37.

To close the switch 33, the combination of the tumblers 23 is first "worked" to aline 110 the notches 24 in position to receive and

clear the end 38 of the bar 29; then the bar may be thrust inward by pressing against its outer or knob end 39, and will close the switch 33.

5 In arranging for the operation of mechanism for giving an alarm when a trial movement of the bar 29 is attempted, the end 38 of said bar, in its "locked" or initial position shown in Fig. 4, is spaced far enough 10 from the tumblers 23 to allow a limited portion of its full switch-throwing stroke before being positively stopped by said tumblers.

15 The alarming mechanism includes a spider 40, which is pivoted on a stud 41 supported by the top 12.

This spider 40 is provided with an arm 42 in the outer end of which a small roller 43 is pivoted.

20 The V-shaped end 44 of a leaf spring 45, which is secured to the wall 15, rests yieldably against the periphery of the roller 43, and when a dead-center line B-B through the pivot of said spider and the pivot of 25 the roller passes the contact point of said V-shaped end 44 in either direction the spider flips to the limit of its throw in said direction.

30 A second arm 46 of the spider 40 projects along the bar 29 and, with the bar at the outer extreme of its throw as in Fig. 4, rests slidably against a stop 47 on said bar under the influence of the spring 45.

35 When the bar 29 is pressed in against the tumblers 23, as in an attempt to "feel" for the alinement of said tumblers, the stop 47 on the bar is carried to where the arm 46 of the spider 40 drops in behind it into the 40 position shown in Fig. 5 under influence of the spring 45.

45 A switch 48, supported on a block 49 secured to the cover 12, is operatively connected to the arm 46 through a connecting rod 50, so that the dropping-in movement of said arm 46 closes said switch and completes circuit through a bell 51.

50 The wiring 52 for the bell 51 may lead from the switch 48 out of the casing 10 and through the conduit 37 to a proper source of current.

55 The face 53 of the stop 47, on the line C-C, is at such angle with the radial line of length of the arm 46 that no withdrawing force exerted on the bar 29 can swing said arm out in a direction to open the switch 48.

60 To swing the arm 46 outward and open the switch 48, the tumblers 23 and disk 27 may be alined by the person knowing the combination, and the full switch-throwing stroke of the bar 29 may be completed; and in completing said stroke a second stop 54 on said bar engages a short arm 55 on the spider 40 and swings said spider to where 65 it will flip to the extreme position shown

in Fig. 6, this movement of the spider opening the switch 48 and stopping the action of the bell 51.

With the ignition switch 33 thus closed, the automobile may be driven away; or if it 70 is not desired to so use the vehicle the bar 29 may be drawn outward its full throw to open said switch; and during this outward movement of the bar a third stop 56 thereon engages the arm 55 of the spider 75 40 and swings said spider to where it will flip its arm 46 into contact with the stop 47 in the initial position shown in Fig. 4 and thus open the switch 48 of the bell 51.

After the bar 29 has been withdrawn to 80 this position, the tumblers 23 and disk 27 may be thrown out of alinement by use of the knob 25 as in other combination locks.

In order that the three stops 47, 54, and 56 may be adjusted in position on the bar 85 29, they may be in the form of tight-fitting nuts which are screwthreaded and engage screw threads on said bar.

The following is claimed:—

1. In a device of the class described, an 90 inclosing casing, a member manually movable in the casing and adapted to control a switch, releasably locking means in the casing adapted to positively stop switch-controlling movement of said member at a 95 point intermediate its full stroke, a stop on the movable member, a spring actuated detent pivoted in the casing and lying in slidable contact with said stop, said detent being adapted to drop, behind said stop upon 100 an initial movement of said member, and means whereby dropping movement of the detent sounds an alarm.

2. In a device of the class described, an 105 inclosing casing, a member manually movable in the casing and adapted to control a switch, releasable locking means in the casing adapted to positively stop switch-controlling movement of the member at partial completion of its full stroke, a stop on the 110 movable member, a spring-actuated detent pivoted in the casing and lying in slidable contact with said stop, said detent being adapted to drop behind said stop upon an initial movement of the switch-controlling 115 member, means whereby dropping movement of the detent sounds an alarm, and means whereby completion of the full stroke of the switch-controlling member swings the detent from behind said stop. 120

3. In a device of the class described, an 125 inclosing casing, a member manually movable in the casing and adapted to control a switch, releasable locking means in the casing adapted to positively limit switch-controlling movement of said member to a partial stroke, a detent pivoted in the casing and adapted to lie in sliding contact with said stop, means acting yieldably to hold said detent away from an intermediate point 130

in its full throw, said detent being adapted to drop behind said stop upon an initial movement of the switch-controlling member, means whereby dropping movement of

5 the detent behind said stop sounds an alarm, and means whereby completion of the full stroke of the switch-controlling member

swings said detent to and past the aforesaid intermediate point in its full throw.

Witness our hands this 19th day of April, 1920.

WILLIAM S. WILLS.
ROBERT A. ROGERS.
